UNITED STATES PATENT OFFICE.

JOSEPH E. ALLEN, OF STAMFORD, CONNECTICUT.

CHANGEABLE NUMBERING DEVICE.

1,193,963.

Specification of Letters Patent. Patented Aug. 8, 1916.

Application filed September 12, 1912. Serial No. 719,914.

To all whom it may concern:

Be it known that I, JOSEPH E. ALLEN, a citizen of the United States, residing at Stamford, county of Fairfield, and State of Connecticut, have invented certain new and useful Improvements in Changeable Numbering Devices, fully described and represented in the following specification and the accompanying drawings, forming a part of 10 the same.

This invention relates to certain improvements in changeable numbering or lettering devices, and it is the especial object of the invention to provide a device having 15 changeable numbers or letters held securely in a frame of improved construction which may be used for numbering or lettering houses, stores, streets and the like, the numbers being so constructed and held in position that any one of them, where more than 20 one numeral or letter is used, may be readily changed without having to remove all the numbers or letters from their securing frame.

25 A further object of the invention is to construct the numbers and so arrange them in the frame that they will stand out plainly and be readable at a distance, both in the day time and at night.

30 A further object of the invention is to produce a device of this character which may be readily and quickly assembled, without special preparation or measurement, which shall be simple, and which shall be so 35 constructed as to prevent, as far as possible, access of dirt, thereby keeping the numbers clean and visible.

40 A convenient arrangement for carrying out these objects of the invention is illustrated in the accompanying drawing, and such will now be described in connection therewith.

In the drawing—Figure 1 is a front view 45 of the device with the various parts assembled, two numbers being shown in the illustration; Fig. 2 is a back view of the construction shown in Fig. 1, certain parts being broken away and certain other parts being shown in a different position; Fig. 3 is 50 a vertical section on the line 3—3 of Fig. 1; Fig. 4 is a cross-section on the line 4—4 of Fig. 2, and Fig. 5 is a view of one of the metal blanks with the number cut or stamped out therefrom.

55 Referring now to these drawings, the invention in its preferred form embodies a

frame 1. The frame is of the desired dimensions to accommodate numbers of the required size. The frame 1 is made in suitable sizes to accommodate one, two or as 60 many of the number blanks as may be required. The frame is formed preferably by stamping or bending sheet metal to provide what may be termed front flanges 2, side flanges 3, and a bottom flange 4, these flanges 65 being all integral with each other and in the same plane. The front flanges are preferably formed as narrow as possible and yet afford a suitable rest or abutment for the various parts of the device which are to be 70 assembled in the frame. The side flanges and bottom flanges are of a depth sufficient to accommodate the various elements of the device hereafter referred to. The bottom flange and the side flanges are furthermore 75 provided with a plurality of holding projections or lugs 5 which may be conveniently formed at the same time that the frame is stamped, these projections being arranged to be bent inwardly in the same plane as 80 illustrated in Fig. 2. On the bottom flange certain of the lugs, as 6, may be formed somewhat wider than the others. These wide lugs 6 are provided at certain points where the meeting edges of two number 85 blanks will abut, this construction being adopted to more firmly hold the numbers in position.

For holding the various parts of the device rigidly in position there is provided a 90 backing piece 7 which is slidable beneath the lugs 5 as illustrated in Fig. 2. The back piece 7 is furthermore provided with a top flange 8, shown in Fig. 1, which laps over the upper edges of the various parts when they 95 have been assembled and on to the edge of the top flange 2 of the frame, this construction acting to prevent, to a large extent, dirt from entering the frame.

The numbers,—numbers being shown in 100 the present instance, although it will be understood letters may be used if desired,—are preferably formed by being cut out of thin metal blanks or sheets 9. These metal blanks are all formed of the same size and are of 105 suitable dimensions to give the required size to the numbers. In order that the numbers may be seen plainly, the blanks are arranged in the frame with a contrasting background, that is, a background formed of a color so 110 as to make the number stand out plainly. This effect can be produced in various ways,

In the construction illustrated the number blanks 9 from which the numbers are cut out are of blackened metal and the blanks when positioned in the frame are backed with a 6 backing of a white material such as a thin white celluloid sheet 10. This has the effect of making the numbers stand out, as it were, so that they are very easy to read at a distance, or in a dim light. This effect can be 10 further increased by placing before the number blanks a facing of some transparent material, such as a sheet of glass, 11.

In assembling the device the sheet of glass is first placed in the frame and abuts against 15 the front flanges 2. The required numerals are then placed in position, the backing of celluloid placed on them, and then the back piece inserted and slid beneath the holding projections on the frame.

20 The invention has been shown and described in what is believed to be its most convenient form. Certain changes and variations, however, may be made in the construction of the device without departing 25 from the invention claimed, and the invention claimed is not to be restricted to the exact details shown and described.

What is claimed is:—

A weather-proof changeable numbering

or lettering device, comprising an integral 30 metal frame having top, side, and bottom front flanges in the same plane, side and bottom members at right angles thereto, with inwardly extending lugs in the same plane at the back thereof, in combination with a sheet of transparent material engaging said front flanges, a plurality of similarly sized changeable carriers of thin sheet metal arranged side by side, each having cut out therefrom the configuration of a single letter 35 or number, a backing of a material of contrasting color, and a sliding metal back piece adapted to engage the side and bottom members of the frame and be engaged by the tabs to hold the backing, carriers, and transparent sheet against each other and against the front flanges, said back piece having at the top an inwardly extending flange forming a cover for the top of the frame and protecting the parts contained therein. 40

45 In testimony whereof, I have hereunto set my hand, in the presence of two subscribing witnesses.

JOSEPH E. ALLEN.
